(57) CLAIM

The ornamental design for an ultrasound cabinet, as showing and described.

DESCRIPTION

FIG. 1 is a perspective view of an ultrasound cabinet showing my new design;

FIG. 2 is a top plan view of my design;

FIG. 3 is a front view thereof;

FIG. 4 is a rear view thereof;

FIG. 5 is a right side thereof;

FIG. 6 is a left side view thereof; and,

FIG. 7 is a modified perspective view showing the ultrasound cabinet with a drawer in an opened position.

The broken lines shown are for illustrative purposes only and form no part of the claimed design.
